(Cl. D85—2)

To all whom it may concern:

Be it known that I, Cecil B. Woofter, a citizen of the United States, residing in St. Paul, county of Ramsey, and State of Minnesota, have invented a new, original, and ornamental Design for a Combination Desk Cigarette Container and Lighter, of which the following is a specification, reference being had to the accompanying drawing, forming part hereof, in which:

Figure 1 is a front elevational view of a combination desk cigarette container and lighter showing my new design.

I claim:

The ornamental design for a combination desk cigarette container and lighter, as shown.

CECIL B. WOOFTER.
